UNITED STATES PATENT OFFICE

1,955,748

YARN FEEDING MEANS FOR KNITTING MACHINES

Frank E. Jones, Pawtucket, R. I., assignor to
Hemphill Company, Central Falls, R. I., a corporation of Massachusetts

Application June 6, 1922, Serial No. 566,388

2 Claims. (Cl. 66—133)

This invention relates to yarn feeding means for knitting machines, and particularly to means for feeding a reinforcing yarn to circular knitting machines for varying lengths of portions of successive courses, as, for example, at the heel portion of a stocking for the formation of a so-called high splice, the edges of which are not parallel to each other, but which are inclined, as, for example, to meet or substantially to meet at 10 a point at the back of the stocking.

In order that the principle of the invention may be readily understood, I have disclosed one embodiment thereof in the accompanying drawings, wherein—

15 Fig. 1 is a side elevation of a so-called seamless stocking to the making of the high splice heel portion whereof my invention may be applied;

Fig. 2 is a front elevation of a knitting machine 20 to which my invention may be applied;

Fig. 3 is an end elevation of the mechanism shown in Fig. 2;

Fig. 4 is a rear elevation of the mechanism shown in Fig. 2;

25 Fig. 5 is a plan view of said mechanism;

Fig. 6 is a front elevation on an enlarged scale of a portion only of the mechanism shown in Fig. 2;

Fig. 7 is an end elevation of the upper part of 30 the mechanism shown in Fig. 6 looking from the right;

Fig. 8 is a rear elevation of the upper part of said mechanism; and

Fig. 9 is a vertical section on the line 9—9 of 35 Fig. 5.

My invention, relating as it does, to circular knitting machines, may be applied to or embodied in various types of such machines, but I have chosen to represent the same as applied to

40 a machine of the well known Banner type disclosed in the patent to Joshua D. Hemphill, No. 933,443, dated December 7, 1909. In this type of machine, the needle cylinder is cylindrical and rotates, while the cams remain stationary and

45 although the machine disclosed is for the purpose of producing hosiery, it is obviously not limited to this class of work. I will, however, describe my invention as applied to a machine of the said type without in all respects limiting it 50 thereto.

Generally speaking, the machine includes a rotating needle cylinder 1 mounted on a suitable table 2 constituting a part of the frame of the knitting machine, and as is customary in this 55 type of machine, said cylinder is arranged to be

rotated and reciprocated to form the fashioned and tubular portions of a stocking respectively. The means for effecting the rotary and reciprocatory movements are substantially the same as those shown and described in the said Hemphill 60 patent, and being well known need no further description.

A plurality of yarn feeding elements is provided and which are herein shown as consisting of five pivoted yarn guides 3, 4, 5, 6, 7, all pivoted 65 at 8 upon a partial ring 9 shown in plan in Fig. 5 and itself suitably pivoted at 10 in Fig. 3, so that it may be swung up out of action to afford access to the needles or for any other purpose. The ring 9 is of the type usually employed in the Banner 70 machine equipped with spring beard needles but obviously my invention may be employed in connection with either spring beard or latch needles, and in the latter case a complete circle latch ring 75 would be employed.

Each of said yarn guides, excepting the yarn guide 7 is normally pressed or urged into action by one of a series of levers 11, one of which is indicated in Fig. 6 as mounted at 12 upon a standard 13 rising from the framework of the 80 machine, each lever having attached to its outer or right hand end viewing Fig. 6 a coil spring 14 connected at its lower end to a screw or pin 15 on the standard 13, thus tending to move each of the specified levers into operative position. Such movement of said levers into operative position is, however, at times opposed and overcome by a series of levers, one for each of said yarn guides 3 to 6, one of such levers being indicated at 16 in Fig. 6 as pivoted at 17 upon the standard 90 13 and having connected to its right hand end viewing said figure a wire or link 18 extending downward to and connected to a suitable lever 19 riding upon a suitable cam 20 mounted upon a disk or drum on the cam shaft 21 in a manner not necessary herein to describe, as it is similar to the construction shown in the said Hemphill patent. There being four levers 16 for the four yarn guides 3, 4, 5, 6, it is evident that according to the dictates of the cams upon the disk or drum, the yarn guides 3, 4, 5 and 6 are permitted to act at suitable times, as, for example, to supply a thread for the leg of the stocking, another for the heel, another for the reinforcement of the 95 heel and another for the foot.

In addition to the yarn guides 3, 4, 5, 6, there is provided, as stated, a yarn guide 7, to which this invention more particularly relates, and the purpose of which in the disclosed embodiment of the invention is to provide a high splice reinforce- 100 105 110

ing yarn above the heel and desirably for successively increasing lengths or portions of a series of successive courses constituting said high splice. For that purpose, the said yarn guide 7 is pivoted at 8 and its outer rounded end is adapted to be engaged between the spaced projections 22, 23 of a lever 24 pivoted at 25 upon a bracket 26 extending upward from a standard 27 and having an end 28 adapted to ride upon a pattern drum 29 mounted for rotative and sliding movement upon a shaft 30 itself mounted in standards 31, 32 shown most clearly in Fig. 7 as rising from a bracket 33 secured upon the bed plate of the machine as shown also in Fig. 3. The shaft 30 has a spline 33' thereon which enters a groove 34 in the pattern drum 29, so that the rotation of said shaft 30 compels the rotation of said drum but permits the traverse of the drum lengthwise said shaft by the mechanism hereinafter described.

The said drum 29 has a portion 35 of its surface of reduced diameter and the remaining portion 36 of the surface is of the full diameter of the drum. The reduced diameter portion 35 is of gradually increasing circumferential extent starting from one end of the drum, as is clearly evident from Fig. 5, said portion 35 being spaced or separated from the portion 36 by the walls or edges 37, 38 extending in the curved or inclined lines shown so that in the rotation of the drum, the end 28 of the lever 24 engages or rides upon increasingly prolonged peripheral portions of the reduced diameter portion 35 as the pattern drum is traversed, and thus the yarn guide 7 is moved positively down into action for gradually increasing portions of each of a plurality of successive courses, so as to feed its thread to the needles as a reinforcing thread for the indicated portions of such courses. It will be evident from the foregoing description that the drum has two portions of its peripheral surface of different diameters separated by lines inclined to a line along said surface normal to the ends of said drum.

At the commencement of the reinforcing action of the yarn guide 7 the drum 29 may be assumed to be in the position shown in Fig. 7 and at that time the said yarn guide 7 is permitted to feed its reinforcing yarn for the minimum length of time dependent upon the short peripheral extent of the portion 35. This would provide for reinforcement at what may be termed the point of a high splice reinforcement at the centre of the back of the stocking. As the drum 29 is traversed axially at a uniform speed, the yarn guide 7 will periodically be positively moved down into action for successively increasing lengths of partial courses, so that a reinforcement tapered from a point or substantially a point in opposite directions down to the opposite sides of the heel 60 is provided, as indicated at 39 in Fig. 1, after which the regular reinforcement for the heel pocket is provided by another yarn guide for that purpose.

It will be understood that so long as the yarn guide 7 is controlled by the pattern drum 29 said yarn guide will be moved into and out of action for successively increasing lengths of time for the purpose stated. At other times, however, the said yarn guide 7 is held positively out of action by one of the series of levers 16, it being understood that the number of said levers 16 is equal to the entire number of yarn guides 3 to 7. Furthermore the lever 16 for the yarn guide 7 will be so controlled that it will move the end 28 of the lever 24 slightly above and out of contact

with the pattern drum 29 whenever said drum is not functioning, and this non-functioning position of the yarn guide 7 and its lever 16 will also occur during the reverse movement or traverse of the pattern drum 29, that is, the movement thereof toward the right viewing Fig. 7.

Any suitable means may be provided to rotate and to traverse the pattern drum 29. Herein for the purpose I have provided the following mechanism. Fast upon the shaft 30 is a beveled gear 40 meshing with two beveled gears 41, 42, each normally loose upon an upright shaft 43 supported in extensions 44, 45 of the bracket 32 and having fast upon its lower end a beveled gear 46 meshing with and driven by a beveled gear 47 upon a suitably supported shaft 48, also having fast thereon a gear 49 which meshes with and is driven by the large gear wheel 50 on the main drive shaft 51 of the machine.

The beveled gears 41, 42 are adapted periodically to be alternately clutched to the shaft 43 and therefore periodically alternately to rotate the shaft 30 in opposite directions, the gear 41 being employed to rotate the pattern drum 29 while the same is being traversed toward the left viewing Fig. 7, and the beveled gear 42 being employed to rotate said pattern drum when the same is being traversed toward the right in Fig. 7. The clutch for alternately connecting the beveled gears 41, 42 to the shaft 43 is indicated at 52 in Figs. 4, 7 and 8, said clutch having members 53, 54, adapted to interengage with corresponding formations upon the beveled gears 41, 42, to effect the functioning and non-functioning traverses of the pattern drum 29, after which said gears 41, 42 stand or remain unclutched until the time occurs to form the high splice upon the next stocking.

In order to shift the said clutch at the proper times, it is mounted upon one end of a lever 55 pivoted at 56 upon the standard, and having connected to its opposite end at 57 a wire or link 58 extending downward to and pivotally connected at 59 to a lever 60 itself pivoted at 61 upon the framing of the machine. The opposite end of said lever 60 is provided with a nose 62 bearing upon a cam 63 upon the cam shaft 21. Said cam 63 is provided with an elevation 64 and so long as the nose 62 of the lever 60 is in engagement with the cam 64, the gear 41 is clutched to the shaft 43 with the result that the pattern drum 29 is rotated and traversed toward the left viewing Fig. 7, so as to cause the yarn guide 7 to present its yarn or thread for increasing lengths of time to the needles and thus to form a tapered high splice in the manner already described, it being understood that the yarn of the yarn guide 7 for those parts of the high splice courses wherein said yarn is not fed to the needles, may be and desirably is floated until reintroduced and is cut out after completion of the knitting.

Immediately succeeding the cam 64 is a depression 65 which is below the level of the cam 63 and when the nose 62 of the lever 60 rides in said depression 65, the bevel gear 42 is splined to the shaft 43 and the drum 29 is rotated and traversed toward the right viewing Figure 7, so as to return the pattern drum to its initial position. This is the non-functioning traverse of the pattern drum and during such return movement of said pattern drum the yarn guide 7 is not permitted to be thrown into and out of action by the pattern drum 29 but the said yarn guide is held out of action by the lever 16 therefor in the manner already described.

The cam portion 63 is of a height intermediate

between the elevation 64 and the depression 65 and said cam 63 also serves to hold the yarn guide 7 out of functioning relation with respect to the pattern drum 29, so that said yarn guide does not 5 function. The length of the cam portion 63 corresponds to length of time that the pattern drum 29 remains stationary, without either traversing or rotatory movement, inasmuch as neither gear 41 or 42 is clutched to the shaft 43. In other 10 words the yarn guide 7 is permitted to function by throwing its yarn into engagement with the needles and withdrawing it therefrom for successively increasing lengths of time or portions of courses, only while the nose 62 of the lever 60 15 is in engagement with the cam 64.

Any suitable means may be provided to traverse the pattern drum 29. Herein for that purpose I have provided a gear 66 upon the shaft 30 shown most clearly in Figs. 5 and 7 as meshing with 20 a larger gear 67 upon a worm or screw 68 mounted in the brackets 31, 32 in parallelism with the shaft 30. The speed of rotation of the worm is such as to cause the pattern drum 29 to be traversed at the proper speed to form the tapered high splice already described.

In order to cause the rotative movement of the worm 68 to be conveyed to the drum 29 and result in a traversing movement of the latter, I have provided upon one end of the drum a ring like 30 member 69 which encircles the shaft 30 with capacity of slight circumferential movement with respect to said shaft 30, for which purpose said member 69 is provided with curved slots 70 receiving screws 71 in a washer 72 by which said 35 washer is secured to the end of the pattern drum 29. The said ring like member 69 is provided with a radial arm 73 carrying a half nut 74, the threads whereof engage those of the worm 68. The said half nut 74 is held in yielding driving 40 relation with the worm 68 by means of a plunger 75 received in a recess 76 of the nut 74, the said plunger itself being hollow and receiving therein a coiled spring 77 which at one end presses at 78 against the half nut 74 and at the other end 79 against the plunger 75. The said plunger 75 45 bears against the inclined face 80 of a bracket 81, the said face being of sufficient length to receive the plunger during the entire traversing movement of the pattern drum 29 and hence during 50 that entire time to hold the half nut 74 in driving relation with the worm 68.

It will be evident from the foregoing description that at the commencement of the high splice the pattern drum 29 is in substantially the position 55 shown in Fig. 7 and that at that time the beveled gear 41 is clutched to the shaft 42, so that said pattern drum is rotated and at the same time is slowly traversed toward the left viewing Fig. 7,

and therefore the yarn guide 7 is moved in and out of action so as to supply the yarn to the needles for successively increasing lengths of partial successive courses, and to float the yarn during the remaining portions of said partial courses, until the bottom of the high splice is reached at any suitable point, as, for instance, at the top of the heel pocket. At that time, the toe 62 of the lever 60 rides off the cam 64 into the recess 65 and accordingly the bevel gear 42 is clutched to the shaft 30 and the pattern drum 29 is traversed non-functioning in the opposite direction, during which time the yarn guide 7 is held up in inactive position by its lever 16. When the neutral cam portion 63 is reached, the effect upon the lever 60 is to hold the yarn guide 7 in its non-functioning elevated position. So long as lever 60 rides upon the cam portion 63, the pattern drum 29 remains quiescent, without either rotation or traverse, it being in position to act upon the yarn guide 7 when the tip of the high splice of the next stocking is reached.

Within the scope of my invention the pattern drum 29 may be utilized to reinforce other parts of knitted fabrics, and the contour of its surface 100 may accordingly be varied as required.

Having thus described one illustrative embodiment of my invention, I desire it to be understood that although specific terms are employed, they are used in a generic and descriptive sense and 105 not for purposes of limitation, the scope of the invention being set forth in the following claims.

I claim:—

1. Means for feeding a reinforcing yarn to the needles of knitting machines to produce reinforced areas having non-parallel sides comprising a movable reinforcing yarn finger, a pattern drum having yarn finger controlling formations upon its periphery with which said finger is adapted to cooperate, said drum having its shaft 110 115 provided with a gear, two driving gears therefor, and means periodically to clutch either of said gears to said shaft gear to effect opposite traversing of said drum.

2. Means for feeding a reinforcing yarn to the needles of knitting machines to produce reinforced areas having nonparallel sides comprising a movable reinforcing yarn finger, a pattern drum having yarn finger controlling formations upon 120 125 its periphery with which said finger is adapted to cooperate, said drum having its shaft provided with a gear, two driving gears therefor, and means periodically to clutch either of said gears to said shaft gear to effect rotation and opposite 130 traversing movement of said drum.

FRANK E. JONES.
